UNITED STATES PATENT OFFICE.

ADOLF EMIL WALDEMAR MEISSNER, OF CHARLOTTENBURG, GERMANY,
ASSIGNOR TO THE SIEMENS & HALSKE ELECTRIC COMPANY OF
AMERICA, OF CHICAGO, ILLINOIS.

ROTARY ROCK-DRILL WITH HYDRAULIC FEED.

SPECIFICATION forming part of Letters Patent No. 557,686, dated April 7, 1896.

Application filed February 1, 1896. Serial No. 577,702. (No model.)

To all whom it may concern:

Be it known that I, ADOLF EMIL WALDEMAR MEISSNER, a subject of the Emperor of Germany, residing at Charlottenburg, near 5 Berlin, Germany, have invented new and useful Improvements in Rotary Rock-Drills with Hydraulic Feed, (Case No. 53,) of which the following is a specification.

My invention relates to a rotary rock-drill 10 with hydraulic feed, the object of my invention being to provide an improved construction of rotary drill, whereby hydraulic pressure may be employed for effecting the forward feed of the drill and also for retracting 15 the drill.

It has been the practice, in the employment 20 of rotary drills, to conduct water to the drill-point for facilitating the drilling operation, and where this is done a water-pressure exists which may be utilized for producing the feed of the drill. It is often necessary to employ considerable force in retracting the drill, as, for instance, in the employment of the 25 diamond prospecting-drill, when it is necessary to use considerable retracting force to break off the core. By means of hydraulic pressure the necessary force required for retracting the drill may be provided, and it is therefore desirable so to construct the drill 30 that hydraulic pressure may be utilized both for feeding and for retracting the drill.

In accordance with the present invention, the drill is constructed so that the hydraulic pressure may be employed for advancing the 35 drill during the drilling operation to thus effect the feed, and may also be employed for retracting the drill. In the construction of the drill employed in practice, a pipe or cylinder is employed, which is rotated through 40 suitable driving mechanism. Moving within the driving-pipe and rotating therewith is a pipe or cylinder upon the end of which the drill is mounted. Within the drill pipe or cylinder is provided a piston, mounted stationarily and connected, through ducts or 45 channels extending to the rear of the drill, with a water-supply, whereby water may be admitted to the interior of the drill cylinder or pipe upon one side or the other of the stationary piston. The stationary piston thus

serves as an abutment upon which the water may react in moving the drill-pipe in one direction or the other, according as the water is admitted upon one side or the other of the piston.

The mechanical construction of the drill which I employ in practice is illustrated in the accompanying drawings, in which—

Figure 1 is a longitudinal sectional view through the drill, and Fig. 2 is a view of the 60 drill from beneath.

Like letters refer to like parts in the two figures.

The casing *a* of the drill is surrounded by a ring *a'*, within which the casing may rotate, 65 the ring *a'* being suitably mounted upon standards. A ring *a''* is adapted to be screwed to the casing to maintain the supporting-ring *a'* against longitudinal displacement. A screw *a''* is provided for clamping the casing 70 *a* in any adjusted position within the supporting-ring *a'*. Mounted in a bearing, supported upon the casing, is a beveled gear-wheel *b*, the shaft *b'* of which is adapted to be connected with a flexible shaft for transmitting 75 a rotary motion to the gear-wheel.

The gear-wheel *b* meshes with a beveled gear-wheel *c*, provided upon its face with a block *c'* carrying an annular channel, between the walls of which and the walls of an 80 annular channel provided in the block *c''*, balls *c''' c'''* are provided. The plate *c''* is mounted upon the casting *d*, which is secured to the rear of the casing *a*. To the hub of the gear-wheel *c* the rotating pipe or cylinder *e* is secured by screw *e'*. The pipe *e* carries at its forward end a sleeve *e''*, between which and a cap *e'''*, secured to the end of the casing *a*, balls *e''' e''' e''' e'''* are provided, the balls being adapted to take up the longitudinal 85 thrust of the pipe *e*.

Within the rotating pipe *e* is provided a pipe *f*, upon the end of which the drill is adapted to be mounted. The pipe *f* is capable of longitudinal movement within the pipe 90 *e* and carries a projection *f'* adapted to move within a slot *e''* in the pipe *e*, whereby the drill-pipe *f* is caused to rotate with the rotating pipe *e*, while the longitudinal movement of the drill-pipe is permitted. The forward 95 100

end of the drill-pipe f is adapted to move within the sleeve e^2 , while the rear end carries a piston f^2 , which slides upon the exterior of the feed-pipe g , which extends through the interior of the drill-pipe f and carries at its end a piston g' which closely fits within the pipe f . The feed-pipe g rotates with the pipe e and is connected to the hub of the gear-wheel c by a screw g^2 . The pipe g is provided with a bore g^3 , which extends through the interior thereof from end to end, the bore communicating at the rear end with chamber h , into which water is admitted when the check-valve is in one position, water being thus permitted to pass through the bore g^3 and to impinge against a disk f^4 , provided within the pipe f . When the water is thus admitted, the pipe f is thrust forward to advance the drill. A small hole or opening f^5 is provided in the disk f^4 to permit the passage of a small quantity of water to the drill-point to facilitate the drilling operation. The feed-pipe g is also provided with a duct g^4 , which is annular in form and communicates at the rear end, through openings g^5 , with a chamber h' , to which the water is admitted when the check-valve occupies the proper position. The duct g^4 communicates at the forward end, through openings g^6 , with the interior of the pipe f at the rear of the piston g' . Water may thus be admitted from the chamber h' through the duct g^4 to the interior of the pipe f at the rear of the piston g' , thus retracting the drill-pipe f . To prevent the passage of the water past the pistons, packings g^2 and f^3 are provided in connection with the pistons g' and f^2 , respectively. Likewise to prevent the passage of the water between the pipe g and its bearings at the rear of the drill, stuffing-boxes k and k' are provided. The cap k^2 of the stuffing-box k' is accessible by the removal of the cover d' upon the rear of the casting d , while the cap k^3 of the stuffing-box k is accessible by the removal of the casting d from the rear of the casing a . Water leaking through the stuffing-box k' passes to the chambers h or h' , and thus does not find access to the working parts of the drill. Water leaking through the stuffing-box k passes to the space d^3 . To prevent water which may leak past the piston f^2 from gaining access to the working parts, the slot e^5 is sealed from the outside by a plate e^6 , so that any water that passes the piston f^2 will run forward and pass to the exterior of the drill between the pipe f and the sleeve e^2 , the water being thrown from the machine by means of the protecting-disk l , which also throws off such water as may come back out of the bore-hole.

During the operation of the drill the three pipes e , f , and g rotate together and during the feeding of the drill the check-valve m occupies the position indicated in the figure,

whereby water is admitted through the inner doors of the pipe g to the space in front of the piston g' , a pressure being thus exerted upon the disk f^4 , which effects the forward feeding movement of the drill. When it is desired to retract the drill, the valve m is moved into position to disconnect the chamber h from the water-supply and connect the same with the outlet n' , whereby the water from the chamber h may escape. The chamber h' is at the same time connected with the water-supply and water is admitted through the duct g to the space at the rear of the piston g' , and the pressure exerted upon the piston f^2 forces the pipe f backward, thus retracting the drill. 80

Having described my invention, what I claim as new, and desire to secure by Letters Patent, is—

1. The combination with a rotating pipe or cylinder, of a drill pipe or cylinder rotating therewith and capable of longitudinal movement therein, a stationary piston or abutment within said drill-pipe, a feed-pipe having ducts extending to the opposite sides of said abutment; whereby pressure may be communicated to either side of said abutment to advance the drill-pipe or to retract the same, substantially as described. 85

2. The combination with a rotating pipe or cylinder, of a drill-pipe adapted to be rotated thereby and capable of longitudinal movement therein, a feed-pipe within said drill-pipe and carrying upon its forward end a piston or abutment upon which said drill-pipe is adapted to move, said feed-pipe being provided with a central bore extending to the space in front of said piston or abutment and with an annular duct surrounding said bore and communicating with the space at the rear of said piston or abutment; substantially as described. 90

3. The combination with the rotating pipe e , of the feed-pipe g situated therein and rotating therewith, the piston or abutment g' carried upon the forward end of said feed-pipe, said feed-pipe being provided with a central bore extending to the forward side of said piston and an annular duct communicating with the space to the rear of said piston, the drill-pipe f carrying the end pieces f^2 and f^5 , the chambers h and h' communicating respectively with the bore of the feed-pipe and the annular duct thereof, and the valve m for placing one or the other of said chambers h and h' in communication with a water-supply; substantially as described. 110

In testimony whereof I affix my signature in the presence of two witnesses.

ADOLF EMIL WALDEMAR MEISSNER.
